UNITED STATES PATENT OFFICE.

ALBERT F. STONE, OF MONTCLAIR, NEW JERSEY.

EASEL DISPLAY-BOX.

1,366,333.

Specification of Letters Patent. Patented Jan. 18, 1921.

Application filed October 27, 1919. Serial No. 333,618.

To all whom it may concern:

Be it known that I, ALBERT F. STONE, a citizen of the United States, residing at Montclair, in the county of Essex and State of New Jersey, have invented certain new and useful Improvements in Easel Display-Boxes, of which the following is a specification.

This invention relates to improvements in combined carton and easel display devices and has for its object the production of a box or carton which in addition to forming a container for goods may be readily set up into display position, the cover acting as the easel support for the carton or box.

In the following description of my invention, I shall refer to the accompanying drawings in which—Figure 1 is a perspective view of a box or carton in closed position embodying my invention; Fig. 2 is an end elevation of the cover; Fig. 3, is a vertical longitudinal sectional view of the carton opened into display position with the cover serving as an easel support; Fig. 4 is a sectional view on the line 4—4 of Fig. 3; Fig. 5 is a longitudinal section on the line 5—5 of Fig. 3; Fig. 6 is a plan view of the blank from which the carton is folded; Fig. 7 is a plan view of the blank from which the cover is folded; Fig. 8 is a perspective view of the cover; Fig. 9 is a longitudinal vertical sectional view of another embodiment of my invention; Fig. 10 is a sectional view on the line 10—10 of Fig. 9; Fig. 11 is a horizontal sectional view on the line 11—11 of Fig. 9; and Fig. 12 is a plan view of the blank from which the carton shown in Figs. 9, 10 and 11 is folded.

Referring to the form of carton shown in Figs. 1 to 6, the blank illustrated in Fig. 6, comprises an exterior top section 1, having side sections 2, 2' joined thereto by scored lines of fold and a bottom section 4 joined to the side section 2'. A foldable member 6 having a tongue 6^a is joined to one end of the top section, said member being folded down over the top when the carton is closed and thrown back into the position shown in Figs. 3 and 4 when in display position. Flaps 2^a are foldably joined to opposite ends of the side sections and when folded toward each other are overlapped by the exterior end members 4^a, which are foldably joined to opposite ends of the bottom section and are provided with jointed ends forming tabs

to slide under the top section as shown in Fig. 3. A narrow side flap 4^b, foldably joined to the outer side of the bottom section is overlapped by the side section 2 and preferably pasted thereto as shown in Fig. 4. 60 The manner of folding the blank and constructing the carton will now be evident.

One of the main purposes of my invention is to provide a cover which will serve as an easel to hold the carton in display position. 65 In Fig. 7 I have illustrated a blank for such an easel cover which comprises a top section 20, having triangular side sections 21, 21' foldably joined thereto. The end flap 20^a foldably joined to the top section is overlapped by the flaps 21^a foldably joined to the side sections. These flaps are notched on one side as shown in Fig. 7 to form tongues 22, 22' which interlock in the manner shown in Fig. 2, and securely fasten the flaps together. 75 It will be observed that there is no end flap at one end, this end being left open.

When the carton is closed to form a container as illustrated in Fig. 1, the flap 6 is folded down over the top section and the 80 tongue 6^a is slid through a slot 23 cut in the top of the cover. This tongue assists in holding the cover in position, and, if desired, the lid may be swung back with the flap 6 acting as a hinge to give access to the 85 contents of the carton.

When it is desired to set the carton up in display position, the cover is removed and, after being reversed, is placed against the bottom with the end 21^a adjacent the top of 90 the carton so that the triangular sides 21, 21' will constitute an easel to support the box or carton in an inclined position as indicated in Fig. 3. The flap 6 may then be raised into vertical position to give the box 95 an attractive appearance and display any advertising matter placed thereon. The cover is properly positioned on the box and the latter is attached and held thereon by a tongue 4^c cut in the bottom and which is inserted in the slot 23 as the cover is being 100 slid into the easel position on the bottom of the box.

It will be evident that this easel cover may be used with boxes or cartons of differing constructions. I have shown a modified form of box or carton in Figs. 9 to 12. In this form the blank shown in Fig. 12, comprises a bottom section 31 having foldably jointed end sections 31^a, 31^b, each of 110

which is provided with lateral tabs 31^c which are inclosed between the double side sections. The foot end section 31^b may have an auxiliary foldable member 31^d which 5 may be bent inwardly and pasted on the section 31^b to reinforce it. The side sections comprise two foldable parts 31^c, 31^b. The ends are first bent up and the flaps bent inwardly to extend along the sides. The side 10 portions 31^c are then turned up against the flaps and the portions 31^d folded over the flaps, the tabs 31^e being then bent so that they lie flat against the bottom and are held under the tongues 35. The box is thus 15 securely locked in the folded or carton form, but can be readily unfolded and laid flat in the blank form by first slipping the tabs 31^e from under the tongues 35. As in the form previously described, when the carton 20 is to be closed, the flap 6 is folded down over the carton and the tongue 6^a is inserted in the slot 23 in the cover in the manner shown in Fig. 1. When the carton is secured to the cover in the manner described in connection 25 with the first form to form an easel, the flap 6 is turned back so that the parts are then as shown in Figs. 9 and 10.

In both forms the cover forms the lid of the closed carton and an easel support to 30 hold the carton in an inclined display position. In both positions the lid is attached to the carton by a tab which enters a slot in the cover. Instead of cutting the sides

of the cover into triangular form as shown in Fig. 7, they may be made rectangular in 35 the blank and may be folded in this form as illustrated in Fig. 8 and the outer triangular portion may then be broken off along the dotted line or be cut off to leave the triangular sides. 40

I claim:—

1. A carton or box formed from a single blank having at one end a free flap foldably joined to one end of the top section which may be raised into vertical position to serve 45 as a sign card or folded down over the top to serve as a locking member for securing the cover, the bottom of said carton having a tab cut therein, and a cover having triangular sides and a transverse slot in its top portion constructed to receive said flap when serving as a cover for the carton and to receive said tab when placed in reverse position against the bottom of the carton to serve as an inclined easel support. 50

2. A carton having a tab cut in its bottom portion and a cover having triangular sides and only one end, the top portion of the cover having a transverse slot cut therein constructed to receive said tab when the 60 cover is placed against the bottom of the carton in reversed position to serve as an inclined easel support.

In testimony whereof I affix my signature.

ALBERT F. STONE.
